COVERED TUBULAR MEMBER FOR POSITIONING IN WELL FLOW PIPE

Gerhard J. Duesterberg, Houston, Tex.

Application September 8, 1958, Serial No. 759,451

5 Claims. (Cl. 138—64)

The present invention relates to a tubular member adapted to be positioned in the flow string of an oil or gas well.

Quite often in the drilling of an oil or gas well, more than one producing strata or formation is uncovered. In order to flow the well fluids to the earth's surface, it is desirable to provide a conduit for communicating separately with each producing formation. It is also desirable to separate, or close off, communication between the various producing formations from each other in the well bore. A great deal of difficulty has been encountered with the flow pipe which extends through one producing formation on down to a lower producing formation, in that as well fluids are discharged from the formation and into well pipe, they tend to cut out the pipe and thereby necessitate repair or replacement of the pipe at frequent intervals.

As a matter of fact, it is not uncommon for well pipe in high pressure areas to be completely eaten out in a matter of days, and, of course, this is extremely troublesome and expensive as a great deal of time and effort is required to replace the pipe, particularly when it is located one to three miles in the earth's surface, and where the oil or gas well is located in relatively inaccessible areas such as in water covered areas in the bay or open sea.

The present invention is directed to a device for overcoming this problem, in that it provides a tubular member adapted to be secured in the well string which inhibits cutting out of the well string and thereby permits the well to flow over an extended period of time without requiring repairs or replacement to the well string.

An object of the present invention is to provide a covering for a portion of the well pipe to resist eroding or cutting out of the well pipe by fluid flow therearound.

Still a further object of the present invention is to provide a covering for a well pipe, said covering including a hard, brittle, substantially non-machinable and molded material with a resilient material on each side of said brittle covering to act as a shock absorbing medium to inhibit damage to the hard, brittle material as the tubular member is positioned in the well string for use.

Other objects and advantages of the present invention will become more readily apparent from a consideration of the following description and drawings wherein:

Fig. 1 is a broken vertical sectional view illustrating the present invention positioned in a well string for use; and

Fig. 2 is a broken quarter-sectional view illustrating the details of construction of the present invention.

Attention is directed to Fig. 1 of the drawings, wherein a well bore is illustrated at 2, such well bore being provided with a casing 3 which is positioned in the well bore when the drilling operations are completed. The present invention will be described with regard to its use where there are two producing formations in communication with the well bore, but it should be appreciated that it can be equally used in any situation where it is desired to eliminate the cutting action of abrasive fluids, or fluids under high pressure, and regardless of the number of pro-

2

ducing formations. A producing formation is illustrated at 4 and another formation is illustrated at 5 spaced below the formation 4. In actual practice, the distance between the formations 4 and 5 may be a relatively few feet, or it might be a few hundred feet or several thousand feet.

In order to accommodate flow from the formation 4 and the formation 5, the casing 3 is provided with a plurality of perforations as shown at 6, in order that the fluids may flow from each of the formations 4 and 5 and into the casing 3 to thereafter be flowed to the earth's surface. It is desirable to provide a flow tube for each formation and as shown in Fig. 1 of the drawings, the pipe or tubing 8 extends downwardly from the earth's surface and terminates adjacent the formation 4 as illustrated at 9. The lower end of the pipe 8 is perforated as shown at 10 so that the well fluids passing into the casing 3 from the formation 4 may be conducted inwardly of the pipe 8 for passage to the earth's surface. Similarly, a flow pipe 11 is provided which extends downwardly in the casing 3 to terminate adjacent the lower producing formation 5 as illustrated at 12, it also being provided with a perforate section 13 at its lower end so that well fluids from the formation 5 may flow into the tubing 11 for flowing to the earth's surface.

It is desirable to separate the producing formations 4 and 5 from each other and from the top of the well bore. This may be accomplished by positioning packers 14 and 15 as illustrated in Fig. 1 of the drawings, in a manner well known in the art. It will be noted that the flow of well fluids from the producing formation 4 through the perforations 6 in the casing 3 will hit the portion 16 of the tubing 11 which extends between the packers 14 and 15. Generally, the producing fluids, whether oil or gas, are abrasive, and quite often enter into the casing 3 under substantial pressure.

Heretofore a great deal of difficulty has been encountered in that the portion 16 of the tubing 11 is quickly cut out by the entering well fluids, thereby necessitating that the well be worked over for repair or replacement of that portion of the tubing 11 which has been eroded or cut out by the well fluids entering into the casing as described above.

I have discovered that this problem can be overcome by positioning a joint of pipe in the tubing string 11 which is provided with a covering for inhibiting cutting out or eroding thereof by the high pressure, or abrasive well fluids entering into the casing 3. If desired, more than one joint of pipe can be provided with the coating so as to provide a suitable length of connected joints to span between the packers 14 and 15, as necessary, in order to provide a portion of the tubing string 11 which is fully protected from the action of the well fluids which enter the perforations 6.

The form of the invention is best illustrated in Fig. 2 of the drawings, wherein a joint of pipe or tubular member is illustrated at 20. The tubular member 20 may be of any suitable length, and normally pipe joint lengths are 20, 30 or 40 feet, and the covering designated generally at 21 will be provided substantially the whole length of the joint of pipe so as to fully protect it from the cutting action of the well fluids as they enter the perforations 6 and hit against the portion 16 of the tubing string 11. As shown in Fig. 2 of the drawings, the tubular member 20 may be machined on its outer surface 22 so as to provide a recess as illustrated at 23 and a shoulder as shown at 24 thereon. An annular ring member 25 is seated on the shoulder 24 and supports one end of the covering on the tubular member 20. The ring or collar 25 may be secured to the remainder of the covering by any suitable means such as welding as illustrated at 26 for holding the covering and the

tubular member 20 together. A collar 25' is positioned on the other end of the covering 21 as shown in Fig. 2 of the drawings, and may be provided with circumferentially arranged openings 27 for receiving set screws 28 therein for locking the collar 25' in position on the member 20 and against the upper end 29 of the covering as shown in Fig. 2 of the drawings. Also, a weld 26 may be arranged on the collar 25' and the covering 21 for locking the covering in position at its other end to inhibit movement thereof as the tubing string 11 is lowered into position in the well bore.

The covering 21 includes a coating of resilient material such as rubber or the like as illustrated at 30. The coating 30 may be arranged on substantially all of the outer surface 22 of the tubular member 20 in strip form 31 as shown in Fig. 2 of the drawings. The coating 30 of resilient material serves as a shock absorber to protect the sleeve member 32 from breakage or damage as the tubing string 11 is lowered into position in the well bore 2. The sleeve 32 covers the entire surface of the member 20 between the collars 25, 25' which collars are adjacent each end of the pipe or member 20. The sleeve 32 is formed of hard, brittle material to resist the cutting action of the high pressure well fluid which strikes thereagainst as it passes through the perforations 6 in the casing 3.

As shown in Fig. 2 of the drawings, the sleeve 32 may be formed by a plurality of tubular members 33 which are in end to end interfitting or overlapping relation as shown in the drawings. More particularly, attention is directed to Fig. 2 of the drawings wherein it will be noted that each of the tubular members 33 is provided at its ends 35 and 36 with recessed portions as shown at 37 and 38 respectively, whereby adjacent tubular sections may be interfitted therewith so that the ends of adjacent sections overlap each other. In this manner, the surface 20 of the well pipe or tubular member 22 is completely shut off from any fluid action, since it would be virtually impossible for any fluid at any appreciable pressure to leak along the line of contact 39 between the overlapped end portions of the tubular members 33. Generally speaking, the tubular members 33 may be of any suitable lengths, and a suitable number may be provided to cover the surface 22 of the tubular member 20. A second layer of resilient material as shown at 40 is provided on substantially all of the outer surface 41 of the sleeve 32, such resilient material being of rubber or the like and acting as a shock absorber to protect the sleeve 32 from breakage or damage as the tubular member 32 and connected pipe sections are lowered into position in the well bore.

In order to further protect the sleeve 32, an outer shell of metal as illustrated at 42 may be provided which extends from the collar 25 to collar 25' as shown in the drawings, and is secured to each collar by means of the welds 26 as previously described herein.

The sleeve 32 may be formed of ceramic or tungsten carbide, or any other suitable hard brittle material which will resist the eroding or cutting out action of high pressure well fluids flowing thereagainst. Generally speaking, materials of this type are substantially non-machinable and are usually molded to the desired configuration or form; it has been discovered that ceramic serves the purpose quite well.

It has been found that when the tubing string is pro-

vided with a section or portion 16 having the covering 21 as described herein, the flow action of the well fluids against the pipe will be resisted and the flow string 11 in which the covered pipe or tubular member 20 is positioned will remain in service over a substantial period of time.

Broadly the invention relates to a coated or covered tubular member for resisting the eroding or cutting out action in well bores by fluid action thereagainst.

What is claimed is:

1. As an article of manufacture a tubular member adapted to be secured in a well pipe string and having threads adjacent each end thereof for securing the member in the well string, a protective coating on said pipe to resist eroding action of well fluids under pressure, said coating including, a rubber sleeve adjacent the outer surface of said member, a tubular ceramic lining surrounding and enclosing said rubber sleeve, a rubber coating covering the exterior of said ceramic lining, and a metallic sheath surrounding and enclosing said rubber coating, and annular abutment means at each end of said protective coating engaged with said tubular member and said metallic sheath to position said protective coating on said tubular member.

2. The combination recited in claim 1 wherein ceramic lining is formed by a plurality of tubular members stacked in end to end interfitting relation.

3. A device for inhibiting cutting out of well pipe by high pressure fluids including a tubular member having threads for connecting said member with the well pipe, a wear resistance covering on said member to inhibit cutting out thereof by well fluids, said covering extending substantially the full length of said member, said covering including a hard, brittle, substantially non-machinable and molded material, and a resilient material on each side of said brittle covering to act as a shock absorbing medium as said tubular member is positioned for use.

4. A device for inhibiting cutting out of well pipe by high pressure fluids including a tubular member having threads for connecting said member with the well pipe, a wear resistant covering on said member to inhibit cutting out thereof by well fluids, said covering extending substantially the full length of said member, said covering including a hard, brittle, substantially non-machinable and molded material, a resilient material on each side of said brittle covering to act as a shock absorbing medium as said tubular member is positioned for use, and means for securing said covering on said tubular member.

5. The combination recited in claim 4 wherein said securing means includes annular collar members at each end of said covering and secured on said member and to said covering for holding said member and covering together.
